UNITED STATES PATENT OFFICE.

JAMES B. JOHNSTON, OF PHILADELPHIA, PENNSYLVANIA.

ICE-MACHINE.

1,386,625.

Specification of Letters Patent. Patented Aug. 9, 1921.

Application filed May 8, 1918. Serial No. 233,231.

To all whom it may concern:

Be it known that I, James B. JOHNSTON, a citizen of the United States, residing in the city and county of Philadelphia, State of Pennsylvania, have invented a new and useful Ice-Machine, of which the following is a specification.

My present invention consists of a novel ice machine in which vacuum, absorbent, and freezing chambers are employed and wherein provision is made to produce a vacuum in said vacuum chamber, the freezing chamber being surrounded by insulating material.

It further consists of a novel construction and arrangement of a casing and its cover, a novel construction and arrangement of containers, and of a liquid tank, novel means for securing such parts in assembled position, and novel means for effecting a seal.

Other novel features of construction and advantage will hereinafter more clearly appear in the detailed description of my invention.

For the purpose of illustrating my invention, I have shown in the accompanying drawing one form thereof which is at present preferred by me, since the same will be found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents in side elevation an ice machine embodying my invention.

Fig. 2 represents a section on line 2—2 of Fig. 1.

Fig. 3 represents a section on line 3—3 of Fig. 2.

Fig. 4 represents, on an enlarged scale, a vertical section of a portion of the ice machine, the section being taken on substantially line 2—2 of Fig. 1.

Fig. 5 represents, in vertical section, a valve connection employed.

Similar numerals of reference indicate corresponding parts.

Referring to the drawings,

1 designates the outer container of an ice machine, embodying my invention. This outer container is supported on a ring shaped base 2 secured to it in any desired

manner. 3 designates an intermediate container which is spaced from the outer container and contributes to form with it a vacuum chamber 4. Both the outer container 1 and the intermediate container 3 are preferably rounded at their bottoms and are connected with each other only at their upper ends and in such a manner as to seal the upper end of the vacuum chamber 4. The construction employed to form such seal will best be understood by reference to Fig. 4. 5 designates a ring having below its upper end a laterally and inwardly extending flange 6 which forms a seat for a gasket 7 and is deflected downwardly and secured in any desired manner to the intermediate container 3. 8 designates a ring or collar which is externally threaded, and at its lower portion it is deflected downwardly and laterally to form a seat for a gasket 9, and it is then deflected downwardly and secured in any desired manner to the inner face of the outer container 1.

10 designates a layer of insulation which is disposed between the ring 5 and the collar 8 and such parts may be connected together, if desired, in any conventional manner.

11 designates an inner container spaced from the intermediate container and of the same contour and contributing with it to form a chamber 12 which is filled with insulating materials 13 in a molded form and of a desired thickness.

The upper ends of the containers 3 and 11 are connected by a ring shaped plate 14. 15 designates a water tank which is preferably provided with double walls and as illustrated it is of rectangular contour so as to form with the inner container 11 a freezing chamber 16. 17 designates a pipe which extends through the side walls of the containers 1, 3 and 11 and is deflected upwardly to present its open end at the upper end of the freezing chamber 16. This pipe also has a branch 18 leading to a double acting vacuum pump 19 provided with an operating arm 20. The pipe 17 is provided with a valve seat 21 having a port 22 communicating with its open end and the branch pipe 18 and the valve seat 21 also has a port 23 communicating with the open end of the pipe 17 and with the vacuum chamber 4. 24 designates a valve controlling the ports 22 and 23 and having its stem passing through a stuffing box and provided with a handle 25. The cover consists of an outer

shell 26, an intermediate shell 27, and an inner shell 28, all of which are preferably of curved contour. The shell 28 forms a chamber communicating with the water tank and the chamber 16.

29 designates a vacuum or air chamber formed by the shells 26 and 27. 30 designates an absorbent chamber formed by the shells 27 and 28 and such absorbent chamber 10 is filled with hygroscopic material 31. The inner shell 28 is perforated or apertured, as at 32, and the chamber 30 is closed by an annular plate 33. The vacuum chamber 29 is sealed in substantially a similar manner 15 to that already described with reference to the vacuum chamber 4. As seen in Fig. 4 the shell 27 has secured to it in any desired manner an internally threaded collar 34 having an inwardly extending flange 35 20 which is provided with an annular bead 36 which seats in the gasket 7 when the cover is secured in position. 37 designates a ring shaped plate connected with the outer shell 26 and provided with an outwardly extending flange 38 which has an annular bead 39 25 which seats in the gasket 9.

40 designates a layer of insulation secured between the members 34 and 37 in any desired manner. 41 designates an annulus 30 cured to the shell 26 and adapted to extend over the joint formed between the body portion of the machine and its cover.

The cover is provided with a grasping handle 42. When the cover is closed the 35 outer insulating chambers substantially surround the absorbent chamber and serve as insulation to protect the inner chamber from induction. If water is present and the vacuum is produced by actuating the handle 40 20 the temperature will lower as the evaporation takes place.

It will be understood that when the vacuum pump is working the valve 24 is open and when the desired vacuum has been 45 obtained the valve is closed, the result of which is evident to those skilled in this art.

It will now be apparent that I have devised a novel and useful construction of ice machine which embodies the features of advantage enumerated as desirable in the statement of the invention and the above description, and while I have, in the present instance, shown and described a preferred embodiment thereof which will give in practice 50 satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:

1. An ice machine, having an outer 65 vacuum chamber, a chamber containing in-

sulating material and located inwardly of the vacuum chamber, a freezing chamber located inwardly of the insulating chamber, a tank in said freezing chamber, a closure having a plurality of superimposed chambers, the lower wall of which is apertured 70 to permit communication between the freezing chamber and lower chamber of the closure and vacuum producing means communicating with the upper end of said freezing 75 chamber and with said vacuum chamber.

2. An ice machine, comprising a plurality of casings spaced from each other and forming an outer vacuum chamber, a chamber inwardly of the vacuum chamber containing insulating material, a freezing chamber inwardly of the insulating chamber, a tank within the freezing chamber to receive the material to be frozen, a closure having a plurality of superimposed chambers, the lower wall of which is apertured 80 to permit communication between the freezing chamber and the lower chamber of the closure, and means to produce a vacuum in said tank and in said vacuum chamber. 90

3. An ice machine, comprising a body portion formed by a plurality of casings which in turn form an outer vacuum chamber, an insulating chamber inwardly of the vacuum chamber, and a freezing chamber 95 inwardly of the insulating chamber, a tank in the freezing chamber, a closure for said body portion forming a chamber above said tank and in free communication with it, said closure having a chamber containing hygroscopic material in communication with said tank, and a vacuum producing means communicating with the chamber of said closure with said tank and with said vacuum chamber. 100

4. An ice machine, comprising a plurality of spaced casings forming an outer vacuum chamber, a chamber inwardly of said vacuum chamber containing insulating material and a freezing chamber inwardly of the insulating chamber, a tank in said freezing chamber adapted to be surrounded by a cooling medium, a closure detachably connected with said casings inclosing the upper end of said tank and said freezing chamber and 110 provided with a chamber having its inner wall apertured, and vacuum producing means communicating with said vacuum chamber, said freezing chamber, the chamber of said closure and the upper end of said 115 tank. 120

5. An ice machine, comprising a body portion, consisting of a plurality of casings spaced from each other and forming an outer vacuum chamber, an insulating chamber inwardly of the vacuum chamber and a freezing chamber inwardly of the insulating chamber, a tank in said freezing chamber open at its upper end, said freezing chamber being open at its upper end, a closure 125 130

for said body portion, a plurality of insulating members between said closure and said body portion, said closure having a chamber containing hygroscopic material and being provided with apertures communicating with said tank and said freezing chamber, and vacuum producing means

communicating with said vacuum chamber and freezing chamber.
